UNITED STATES PATENT OFFICE

2,636,488

INJECTION CARBURETOR

Oscar R. Cedarholm, Quincy, Mich.

Application July 20, 1950, Serial No. 174,927

16 Claims. (Cl. 123—119)

1

This invention relates to improvements in internal combustion engines and particularly in carburetors adapted to be used in connection with engines of the internal combustion type.

An object of this invention is to provide an injection type carburetor adapted to be used practically with engines of standard description normally found in motor vehicles, which carburetor is simple in construction inasmuch as there is no float, float valve, float chamber and other analogous structure, venturis have been omitted entirely and a large number of moving parts are completely omitted, such as an acceleration pump and all of its structure.

A further object of the invention is to provide a device of the character to be described which may be used for liquid, as water or water mixed with alcohol, for injection thereof into the engine intake system.

Another object of this invention is to provide a carburetor which employs a metering assembly that is synchronized with the butterfly valve whereby fuel flow under pressure is initiated and sustained by the conventional fuel pump which is standard on all engines employed in motor vehicles today.

A further object of this invention is to provide a throat or riser which is adapted to connect with the intake manifold of the engine, said riser having a boss which opens into it and accommodates a displaceable valve body having an axially slideable valve core therein, the boss having a case formed at its upper end with a movable partition therein, for example, a piston or diaphragm upon which suction or negative pressure of the intake manifold may act so as to cause the movable partition to operate and being attached to the valve body causes the valve body to move in response to suction in the intake manifold whereby the valve core moves inwardly of the riser so that it may be located in a position for operativeness or operation by the throttle valve only at such time that a suction is created in the intake manifold. By this expedient when the engine is not operative the valve is displaced to such position that the throttle valve does not appreciably actuate the valve core so that fuel under residual pressure in the fuel pump and fuel pump lines does not cause the engine to be flooded.

A still further object of this invention is to adjustably regulate the extent of travel of the valve body by means of a manual adjustment and also by means of a thermostatic control adjustment, the thermostat being preferably responsive to exhaust manifold heat.

Other objects and features of importance such

2

as high volumetric efficiency in engine operation, accuracy and control in the amount of fuel for all speeds of operation, surety in the proper feed of fuel, and others will become apparent in following the description of the illustrated form of the invention.

In the drawings:

Figure 1 is an elevational view of a typical internal combustion engine used in a standard 10 motor vehicle and having the improved carburetor attached thereto appropriately;

Figure 2 is a longitudinal sectional view of the device showing it in a condition corresponding to a stopped engine;

Figure 3 is a longitudinal sectional view somewhat similar to that of Figure 2 and showing the condition of the various elements after the engine has been started;

Figure 4 is an elevational view of the device, 20 portions broken away in section to illustrate detail of construction and showing particularly various parts in their relative positions corresponding to employment with a hot engine;

Figure 5 is a transverse sectional view taken 25 substantially on the line 5—5 of Figure 2 and in the direction of the arrows;

Figure 6 is a transverse sectional view taken substantially on the line 6—6 of Figure 2 and in the direction of the arrows;

Figure 7 is a fragmentary elevational view of 30 apart of the device showing the crank operator for the butterfly or throttle valve;

Figure 8 is an enlarged sectional view taken substantially on the line 8—8 of Figure 3 and in the direction of the arrows;

Figure 9 is an enlarged sectional view taken substantially on the line 9—9 of Figure 4 and in the direction of the arrows;

Figure 10 is a sectional view taken substantially on the line 10—10 of Figure 3 and in the direction of the arrows;

Figure 11 is a transverse sectional view taken substantially on the line 11—11 of Figure 10 and in the direction of the arrows;

Figure 12 is a perspective view of the abutment forming member for the valve body and displaceable partition;

Figure 13 is an enlarged sectional view of a 45 part of the valve body, core and the connecting assembly;

Figure 14 is a perspective view of the valve core which forms a part of the displaceable valve which meters the fuel; and

Figure 15 is an elevational view of the device 50 showing it employed with a water injection assembly, portions of the riser being broken away in section to illustrate internal details.

In Figure 1 there is a typical engine 10 with a fuel pump 12, an intake manifold 14, an exhaust manifold 16 and an air cleaner 18. These elements are conventional in themselves and are employed with the improved carburetor. A riser or tube 20 is provided with an enlarged upper end 22 upon which the air cleaner 18 is disposed, and a flange 24 at the lower end having openings 25 and 26 therein through which bolts are adapted to pass in order to fix the riser 20 to the intake manifold or the adapter 28 disclosed in Figure 1. This adapter is simply a length of conduit which is attached by means of bolts to the intake manifold 14 and may be used where the throat forming riser 20 does not match exactly with the standard intake manifold throat, otherwise, the riser 20 would be attached directly to the intake manifold 14.

A housing 30 is disposed adjacent the riser 20 and consists of an upper case 32 together with a boss 34 which is integrally connected with the side of the riser 20. A bore 36 is formed in the boss 34 and opens into the riser 20 as well as the chamber 38. A closure 40 is disposed on the outer end of the case 32 and has at least one air vent 42 therein. A central opening 44 is formed in the closure 40, through which the valve body 46 passes.

Said valve body consists of a sleeve which is threaded at its outer end as at 48 so that the flexible conduit 50 may be attached thereto by a conventional coupling. This flexible conduit is secured to the outlet side of the fuel pump 12 and conducts fuel under pressure into the passage 52 in the sleeve 46. There is an enlarged portion 54 of the passage 52 at the inner end of the sleeve and a plug 56 closes the inner end of the sleeve. This plug has a bore 58 therein accommodating the valve core 60. Said valve core is adapted to slide axially within the sleeve 46 and is provided with various passageways so that it serves as a metering valve core.

A longitudinal passage 61 is formed in the core 60 (Figure 3) and opens into the deepest part of a laterally opening notch 62 adjacent the outer end of the core. A plurality of orifices or ports 64 are formed transversely in the metering core 60 and open into the passage 61. These ports are adapted to conduct fuel under pressure which passes through the passage 61, after it has passed through the notch 62 and the bore 52 of the sleeve 46.

In order to control the size of opening and hence the rate of fuel flow through the passage 61, the valve core 60 is adapted to slide inwardly and outwardly of the plug 56 thereby exposing more or less of the notch which is tapered as disclosed in Fig. 14.

A resilient bushing 66, for example rubber, is secured to the inner end of the valve core 60 and is adapted to seat upon the inner surface of the plug 56 thereby forming a stop for the fuel flow. This washer-like member also forms a stop to limit the outward movement of the core 60 with respect to the sleeve or valve body 46.

Means opposing the operation of the valve core is provided. This means consists of a spring 68 which reacts upon and seats upon the abutment 70 in the sleeve 46 formed at the junction of the enlarged portion 54 of the bore and the smaller portion 52 of the bore. This spring also seats upon the inner end of the core 60, constantly biasing or urging the core outwardly of the sleeve 46.

A transverse pivot pin 76 is mounted for rota-

tion across the riser 20 and has a non-circular end 77. A crank 78 to operate the pivot pin 76 is attached to the non-circular end 77 and through the medium of conventional linkage, may be operated by the foot or hand of an individual in a vehicle.

A throttle valve 79 of special description is fixed to the pivot pin 76. A depression forming a pocket 80 in one surface of the throttle valve constitutes a means to accommodate a supply of idling fuel. A port 82 in the pivot pin 76 opens into an aperture 84 in the pocket 80 whereby idling fuel may be drawn therethrough and into the intake manifold 14 of the engine.

A crimp forms a stop 86 in the pocket 80 which is adapted to be engaged by the core 60 for operation of the latter in response to the pivotal movement of the throttle valve 79.

A heat insulating material, as asbestos fiber, spun glass, synthetic rubber and others 84 is disposed in the case 32 at the lower end thereof. A movable partition, such as a piston 83 or a diaphragm is attached to the sleeve 46 and is adapted to be moved within the case 32 to thereby axially displace the valve body 46. A sheet 85 of heat insulating material is attached to the undersurface of the piston 83 for cooperation with the remainder of the insulating material liner. A collar 87 also of insulating material is disposed around a part of the outside surface of a metallic collar 88 which is disposed between the outer surface of a part of the sleeve 46 and a bimetallic thermostat 90. This bi-metallic thermostat is fixed to the collar 88 at one end thereof and is fixed to the case 32 at the other end thereof. Therefore, upon expansion or contraction of the thermostat 90, the collar 88 is rotated.

Threads 92 are provided on a part of the outside surface of the collar 88 and are seated in the threads formed in the boss 34. Therefore, when the collar 88 is rotated in response to changes in temperature within the housing 30, the collar 88 is moved axially.

The upper end of the collar forms an abutment upon which the piston 83 seats or contacts. This limits the axial travel of the valve body 46.

A tongue 94 (Figure 12) extends from one end of the collar 88 and is contacted by the set screws 95 and 96 which form a manually adjustable means for limiting the travel of the collar 88. These set screws are threaded in openings in the boss 34 and by correlating Figures 8 and 9 the position of the collar corresponding to the cool and hot engine are noted.

So that the movement of the thermostat 90 will be a function of the engine heat content, the conduit 98 is attached by means of a conventional coupling 99 to the housing 32 below the piston 83. The conduit 98 is wound in a coil around the exhaust manifold 16 whereby when the engine is operated and hot exhaust gases and products of combustion pass through the exhaust manifold, the air in the coil 100 formed of the conduit 98 becomes heated.

This air is drawn through the chamber 38 below the piston 83 inasmuch as the conduit 101 is secured by means of a conventional coupling 102 to the housing 32 below the piston 83 and also to the intake manifold 14 or the adapter 28. By having the diameter of the conduit 98 smaller than the diameter of the conduit 101 a vacuum will be maintained in the case 32 below the piston 83. In lieu of this expedient, a calibrated orifice may be provided in the line or conduit 98.

In order to adjust the idling speed of the engine,

a manually operable means to serve this purpose is provided. The preferable means consists of a set screw 106 which is threaded in an opening 108 formed in the pivot pin 76. The inner end of the set screw 106 is adapted to enclose a part of the port 82 (Figure 5) in accordance with the adjustment of the screw 106.

In operation, attention is first invited to Figure 2 which shows the condition of the various elements with respect to each other when the engine is off or absolutely cold, as just prior to starting the engine. As soon as the engine is cranked, as by the starter, suction is produced in the intake manifold 14 and hence in the adapter 28, if an adapter is used. This negative pressure is supplied in the chamber 38 below the piston 83 through the conduit or conductor 101. This pulls the piston 83 downwardly thereby displacing the valve body 46 toward the interior of the riser 20. Accordingly, the valve body moves down a sufficient amount, as disclosed in Figure 3, so that operation of the throttle valve 79 will cause the core 60 to be slid inwardly of the valve body 46 an amount sufficient to open the notch 62 allowing fuel under pressure to pass into the passage 61 for emission through the ports 64.

In the condition as disclosed in Figure 2, operation of the throttle valve 79 will not cause enough sliding movement of the core 60 to open the notch 62 for fuel flow.

Accordingly, assuming that the engine has started, the disposition of the valve body 46 will be approximately that disclosed in Figure 3. Then, when the throttle valve 79 is operated, the valve core 60 will be urged inwardly against the opposition of the spring 68 more or less depending upon the degree of actuation of the valve 79. Accordingly, more or less of the notch 62, which is tapered, will be open for fuel flow.

The fuel under pressure is taken from the fuel pump 12, through the line 50, which is flexible, so that a somewhat constant fuel pressure head is always available. While the engine is becoming heated, air is drawn through the open ended coil 100 wrapped around the exhaust manifold 16, through the housing 30 so that it, being heated, impinges upon the thermostat 90 causing it to expand. This expansion rotates the collar 88 inasmuch as the inner end 110 is secured in a slot (Figure 10) formed in the collar 88 and the outer end of the thermostat 90 is disposed in the hook 112 which is formed at the end of the spring liner 114, which is arranged over a part of the liner 81 and held in place.

Accordingly, while the engine is hot the limit of movement of the piston 83 and hence the valve body 46 is set by the upper end of the collar 88 which serves as an abutment. Axial adjustment of this collar is obtained by employing the set screws 95 and 96 as previously described.

For idling, inasmuch as the suction retains the piston 83 in a down position, the valve body 46 is also held down. Only a small amount of the tapered notch 62 is free to receive fuel under pressure from the fuel pump and through the various passages. The fuel will then flow down to the pocket 80 on the outer surface of the core 60. Then, the fuel is drawn through the port 82 and the aperture 84 in order to sustain engine operation at a low or idling speed.

When the engine is stopped, the spring 68 reacting on the core 60 pushes it outwardly of the valve body 46. This tends to urge the piston 83 upwardly. Since the suction in the intake manifold no longer exists, there is no force pulling

against the opposition of the spring 68 and accordingly, the valve body 46 is displaced outwardly of the riser 20 to completely cut off the fuel supply.

Reference is now made to Figure 15. In this instance the metering assembly 118 is passed through the riser 20 for operation by the throttle or butterfly valve 79. Instead of injecting fuel, water or another liquid or mixtures of water and other liquids, as alcohol, are commingled with the fuel charge. In an assembly such as disclosed in Figure 15, a separate water pump 120 to be operated by any suitable engine component is provided with an outlet tube 122 opening into the housing or case 124. A pump inlet pipe 126 is connected to the pump and to a suitable reservoir such as a tank. By omitting the thermostat and its adjustments and adjusting structures water may be injected in amounts which are functions of throttle 79 openings, rather than the usual exhaust and/or intake pressures and vacuums. Due to the fluctuations and changes of exhaust pressures or intake negative pressures the displacement of water is never dependable. But, by relying upon the butterfly or throttle valve 79 for operation, which is controlled by a mechanical linkage, a definite displacement which is a function of the movement of the throttle valve is obtained.

As a subcombination the case 124 with its structural arrangements including the metering valve assembly 118, its metering valve core 128, the pump 120 and the conduits, may be employed with a standard carburetor by simply crimping the butterfly valve to form a pocket therein.

Having described the invention, what is claimed as new is:

1. In an internal combustion engine having an intake manifold, a carburetor comprising a riser, a throttle valve pivoted therein, a valve body mounted displaceably in said riser, a movable partition secured to said valve body, a case within which said partition is disposed and operable, a conductor secured to said case operatively connected with said intake manifold for vacuum actuation of said partition to thereby displace said valve body, a valve core disposed in said valve body and operatively engaging the throttle valve to operate said core in response to movement of said throttle valve when said valve body is displaced inwardly of said riser.

2. In an internal combustion engine having an intake manifold, a carburetor comprising a riser, a throttle valve pivoted therein, a valve body mounted displaceably in said riser, a movable partition secured to said valve body, a case within which said partition is disposed and operable, a conductor secured to said case operatively connected with said intake manifold for vacuum actuation of said partition to thereby displace said valve body, a valve core disposed in said valve body and operatively engaging the throttle valve to operate said core in response to movement of said throttle valve when said valve body is displaced inwardly of said riser, means forming an abutment for said body adjustably disposed in said case to limit the displacement of said valve body.

3. In an internal combustion engine having an intake manifold, a carburetor comprising a riser, a throttle valve pivoted therein, a valve body mounted displaceably in said riser, a movable partition secured to said valve body, a case within which said partition is disposed and operable, a conductor secured to said case opera-

70

5
tively connected with said intake manifold for vacuum actuation of said partition to thereby displace said valve body, a valve core disposed in said valve body and operatively engaging the throttle valve to operate said core in response to movement of said throttle valve when said valve body is displaced inwardly of said riser, means forming an abutment for said body adjustably disposed in said case to limit the displacement of said valve body, a thermostat disposed in said case and operatively connected with said abutment, and means communicating with the interior of said case for supplying heated air thereinto to operate said thermostat.

10
4. The combination of claim 2, and manually adjustable means carried by said case for adjusting said abutment.

15
5. The combination of claim 2, and manually adjustable means carried by said case for adjusting said abutment, means forming a pocket in said throttle valve to support idling fuel, and said throttle valve having an idle fuel port therein opening into said pocket.

20
25
6. The combination of claim 2, and manually adjustable means carried by said case for adjusting said abutment, means forming a pocket in said throttle valve to support idling fuel, and said throttle valve having an idle fuel port therein opening into said pocket, and a manually operable adjustment screw for said port disposed in said throttle valve.

30
35
7. A carburetor comprising a riser for attachment to an engine intake, a throttle valve disposed in said riser, a displaceable valve body passed through an opening in said riser and having a metering valve core therein, the inner end of said metering valve being in contact with said throttle valve for operation of said valve core, resilient means yieldingly opposing the operation of said valve core and opposing the inward displacement of said valve body, adjustable means disposed in the travel path of the valve body and forming an abutment for said valve body to limit the movement of said body, thermostatically operative means for regulating said abutment.

40
45
8. A carburetor comprising a riser for attachment to an engine intake, a throttle valve disposed in said riser, a displaceable valve body passed through an opening in said riser and having a metering valve core therein, the inner end of said metering valve being in contact with said throttle valve for operation of said valve core, resilient means yieldingly opposing the operation of said valve core and opposing the inward displacement of said valve body, adjustable means disposed in the travel path of the valve body and forming an abutment for said valve body to limit the movement of said valve body, thermostatically operative means for regulating said abutment, manually operable means to adjust said abutment.

50
55
60
65
70
9. A carburetor comprising a riser for attachment to an engine intake, a throttle valve disposed in said riser, a displaceable valve body passed through an opening in said riser and having a metering valve core therein, the inner end of said metering valve being in contact with said throttle valve for operation of said valve core, resilient means yieldingly opposing the operation of said valve core and opposing the inward displacement of said valve body, thermostatically operative means connected with said valve body for limiting inward displacement of said valve body.

10
15
10. The combination of claim 1 wherein the engine includes an exhaust, and a further conductor having communication with the interior of the case and being in heat exchange relation with the exhaust.

15
20
25
11. For use with an internal combustion engine of the type including an intake and an exhaust, a carburetor including a riser adapted to be connected to the intake and having a throttle valve, a fuel valving assembly for metering fuel into the riser, comprising a pair of relatively movable elements the relative positions of which determine the rate at which fuel is metered thereby, each of said elements being movable relative to the riser, means operatively connecting the valve to one of the elements to position the latter as predetermined by the valve position, means yieldingly urging the elements to relative positions for restricting the flow of fuel, pressure responsive means adapted to be connected to the intake to urge movement of the other element relative to the riser to increase the flow of fuel whereby the rate of metered fuel flow is governed by pressure within the intake in conjunction with the setting of the throttle valve.

45
12. For use with an internal combustion engine of the type including an intake and an exhaust, a carburetor including a riser adapted to be connected to the intake and having a throttle valve therein, a fuel valving assembly for metering fuel into the riser comprising a pair of relatively movable elements the relative positions of which determine the rate at which fuel is metered thereby, each of said elements being movable relative to the riser, means operatively connecting the valve to one of the elements to position the latter as predetermined by the valve position, means yieldingly urging the elements to relative positions for restricting the flow of fuel, pressure responsive means adapted to be connected to the intake to urge movement of the other element relative to the riser to increase the flow of fuel, a movable stop carried by the riser for limiting movement of said other element caused by the last means, and thermally responsive means adapted to be connected to the exhaust for adjusting the position of the stop.

45
50
55
60
65
70
13. The combination of claim 12, wherein the pressure responsive means includes a case having a movable wall, and outlet conduit communicating with the interior of the case and adapted to be connected to the intake, a relatively smaller inlet conduit communicating with the interior of the case and adapted to be placed in heat exchange relation with the exhaust, said thermally responsive means being disposed in the case.

75
80
85
90
95
14. In a carburetor, a vertically extending riser, a throttle valve in the riser comprising a transverse pivot pin journaled in the riser and a valve plate fixed to the top thereof, said valve plate having a pocket formed in the upper side thereof, a transverse passageway extending through the pin and the plate that opens into the pocket, said pivot pin having an axial bore that opens into the passageway, and an axially adjustable valving element in the bore for controlling flow through the passageway.

15. In a carburetor for internal combustion engines a vertically extending riser, a throttle valve in the riser comprising a transverse pivot pin journaled in the riser and a valve plate fixed to the top thereof, said valve plate having a pocket formed in the upper side thereof, means for introducing fuel into the riser above the valve plate, said means comprising a valve body mounted dis-

placeably in the riser, a movable partition secured to the valve body, a case within which said partition is disposed and operable, a conductor secured to the case and adapted to be connected with the riser below the valve plate for vacuum actuation of said partition to thereby displace said valve body, a valve core disposed in said valve body and operatively engaging the throttle valve plate to operate said core in response to movement of said throttle valve when said valve body is displaced inwardly of said riser, a transverse passageway extending through the pin and the plate that opens into the pocket, said pivot pin having an axial bore that opens into the passageway, and an axially adjustable valving element in the bore for controlling the flow of fuel through the passageway.

5

16. The combination of claim 15, wherein the valve core is provided with a fuel inducting passage therein and extends into the pocket in the valve plate.

OSCAR R. CEDARHOLM.
